UNITED STATES PATENT OFFICE.

RICHARD J. POWELL, OF EVANSCVILLE, INDIANA, ASSIGNOR TO HIMSELF,
WILLIAM F. NOLAN, AND JOHN ROHSENBERGER, OF SAME PLACE.

AWNIN.

SPECIFICATION forming part of Letters Patent No. 333,479, dated December 29, 1885.

Application filed October 9, 1885. Serial No. 179,396. (No model.)

To all whom it may concern:

Be it known that I, RICHARD J. POWELL, a citizen of the United States, residing at Evansville, in the county of Vanderburg, State of Indiana, have invented certain new and useful Improvements in Awnings, of which the following is a specification, reference being had therein to the accompanying drawings.

- 10 This invention relates to certain new and useful improvements in awnings; and it has for its objects, first, to provide a train of gearing and an operating-wheel and band or rope, the latter to extend to within easy reach of 15 the operator, whether his post be on the ground or at a window; secondly, to provide a frame adapted to be secured to the house or structure and to support the awning in taut position; and, thirdly, to provide the awning-pole 20 with a series of anti-friction rollers adapted to run upon the members of the supporting-frame and facilitating the manipulation of the awning.

In the accompanying drawings, forming a 25 part of this specification, and on which like reference-letters indicate the same parts, Figure 1 represents a side elevation of the awning, the frame, and the operating-gearing and band; Fig. 2, a plan view of the frame with 30 the awning removed, and Fig. 3 a detached view of the operating-gearing and the awning-roller.

The letter A designates front of a house or other structure to which the awning may be 35 applied, and to the same are secured, in any convenient manner, a series of metallic rods or pipes, B, in an inclined position. The outer ends of these rods turn downwardly at b, and finally terminate in hooks b', forming seats for 40 the reception and retention against the action of wind of the awning-pole C. These rods are also connected together near their outer ends by a bar, D, and to this latter are secured braces E, the inner ends of which are made 45 fast to the structure, (the house;) also, secured to the permanent structure and near one end of the frame is a bracket, F, which forms a bearing for the adjacent end of the awning-roller G. At the opposite end of the frame is 50 located and secured to the wall or structure the operating-gearing, consisting of the metal-

lic frame H, in which is mounted to rotate the operating-shaft I, carrying the operating band-wheel J and driving-pinion K. This latter meshes with a gear-wheel, L, and that wheel 55 in turn meshes with a gear-wheel, M, mounted on the roller-spindle, the said spindle also having its bearing in the gearing-frame. The band-wheel J is preferably provided with a peripheral groove, in which runs the band or 60 rope N, and which also runs over a sheave, O, fitted upon an adjustable knob, whereby the tension of the band may be increased and the awning held in any adjusted position on the awning-frame. The spindle of the knob works 65 in a slot in the plate P, and the latter is secured in close relation to the post of the frame.

In order to fix the knob in any given position, it may be screw-threaded to agree with 70 a thread on the spindle, and the inner end of the latter enlarged, so as to bind against the inner face of the plate. The awning at one end is secured at intervals to the roller and at the other is likewise secured to, or it may be 75 passed round, the pole C. The pole is provided with a freely-turning grooved anti-friction roller, Q, in proximity to the respective members of the awning-frame, and the spindles of these anti-friction rollers may be 80 secured either to the pole directly or to a metallic strip, and the strip then secured to the pole. Such is the construction illustrated.

The mechanism here described makes the 85 operation of very heavy awnings within the control of a small boy, and the frame is light and strong.

Having thus fully described my invention, what I claim as new, and desire to secure by Letters Patent, is—

9c

1. In an awning, the pulley O, the band N, band-wheel J, pinion K, spur-wheels L M, and roller G, in combination with an awning having a pole, C, provided with grooved anti-friction rollers Q, adapted to fit over and 95 travel upon the metallic rods B, forming part of the awning-frame, substantially as described, and for the purposes set forth.

2. In an awning, the supporting-frame consisting of the rods B, having their inner ends 100 adapted to be attached to the wall of a building and to project therefrom in a downward

direction, and provided with a downward curve, *b*, near their lower ends, and upwardly-turned hooks *b'* at their lower extremities, the horizontal bar *D*, and the braces *E*, in combination with an awning provided with a pole, *C*, having anti-friction grooved rollers *Q*, adapted to fit over and to ride upon the rods *B*, the outer portion of said awning and pole *C* being adapted to hang over the downwardly-curved portion *b* of the rods *B*, and to be held

in place by means of the upwardly-turned hooks *b'* at the lower ends of the said rods *B*, as described, and for the purposes set forth.

In testimony whereof I affix my signature in presence of two witnesses.

RICHARD J. POWELL.
